FIG. 1 is a perspective view of a removable gap closing wedge for automobile seats, showing my new design;
FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

FIGS. 1 through 7 illustrate a right-hand removable gap closing wedge for automobile seats, it is to be understood that the invention includes a left-hand removable gap closing wedge for automobile seats which would be illustrated as a mirror image of any or all of the views shown in FIGS. 1 through 7.
